UNITED STATES PATENT OFFICE

GEORGE EATON, OF CLEVELAND, OHIO, ASSIGNOR TO MAY C. EATON, OF BALTIMORE,
MARYLAND

COMBINED SOCKET AND SNAP SWITCH

Application filed April 27, 1926. Serial No. 104,865.

This invention relates to a combined socket and snap switch and more particularly relates to a socket structure embodying a recoil snap switch wherein the switch will operate to snap on when manually operated and will snap off when released, so that during operation, the switch must be held closed and will snap open when released.

The invention is particularly designed for use in connection with electrically-heated hand tools such for example as sad irons, curling irons or soldering irons.

It is not an infrequent thing for a person using an electrically-heated hand tool to be called away without first cutting off the heating current and this oversight involves dangers such as may arise from overheated irons besides causing a waste of current.

The present invention is directed to a combined socket and snap switch structure for attachment to the electrically-heated hand tool to control the current which snap switch will be manipulated by the hand which controls the tool and which operates to snap on when the tool is grasped and will only remain on as long as it is held by the hand and which will snap off when the tool is released so as to prevent arcing of the current when the circuit is closed or opened.

The invention is illustrated in the accompanying drawings wherein,

Fig. 1 shows a sad iron to which is attached my improved socket and snap-switch,—the parts being shown in side elevation.

Fig. 2 illustrates the detached socket and switch in side elevation.

Fig. 3 shows the same in front elevation with the switch-lever broken off and in section.

Fig. 4 illustrates one-half of the socket and switch body with the connections and parts attached thereto,—the cover portion being removed.

Fig. 5 shows an enlarged cross-sectional detail through the device including the cover

and portraying the structure as the same would appear if viewed on the line 5—5 of Fig. 4.

Fig. 6 illustrates a sectional detail through the switch-frame and actuating lever to disclose the snap-switch yoke and the spring device for snapping the same into engagement or from engagement with the circuit-closing contacts.

Fig. 7 shows the same parts viewed in side elevation.

Fig. 8 illustrates in a diagrammatic way the snap-switch-yoke and the contacts with which it coacts to close or open the circuit, and

Fig. 9 shows the detached snap-switch-yoke in perspective.

Referring to the drawings and particularly Figs. 4 and 5 thereof, the numeral 10, designates one-half of the body member and 11 the other half of the same. The two halves being formed of an insulating material and having recesses or cavities to receive the conductors and switch parts.

In the structure shown the cable 12, enters one end of the body and has one wire 13 thereof extended laterally and connected to a conductor plate 14, that lies in a longitudinal passage or recess 15, in the body-part 10. This conductor plate 14, has one end connected to a clip-terminal 16 that receives one of the usual posts 17, employed on the tool or iron.

The other wire 17 of the cable extends laterally in an opposite direction from the wire 13 and connects with one end of another conductor-plate 18 which latter is carried in a passage or groove 19 in said body-part 10.

This conductor-plate 18, has an off-set free end 20, which forms one blade of a switch while in a plane beneath said end 20 there is another conductor-plate 21 which has a yielding and off-set free end 22 which laps but is in spaced relation with respect to the free end 20.

These two free and yielding ends 20 and 22 therefore together form the two spaced contacts of the switch with which a movable contact element is to make a quick or snap engagement and disengagement when closing or opening the circuit as will presently be explained.

The conductor plate 21, leads to and is connected with a clip terminal 23, that receives another of the two posts 17 usually employed on the tool or iron.

The present invention has nothing to do with the heating element in the tool or iron and the same is therefore not illustrated in the present case.

In order to render the structure more compact, I provide the body-part 10 with a cavity 24 and the body-part 11 with a companion cavity 25, at and adjacent to the point where the two yielding contact ends 20 and 22 are located so that the improved snap switch elements which are to engage and disengage the said contact ends may be entirely concealed and enclosed by said two body-parts.

The snap-switch elements will therefore now be explained reference being made particularly to Figs. 4 to 8 inclusive in the drawings.

30 The switch structure is mounted on a frame including an upper plate 26, a lower plate 27 and spaced apart connecting side bars 28 which connect said two plates at one side only thereby forming a gap or slot 29 between the connecting bars at said one side. At the opposite side the frame is completely open between said upper and lower plates so that the frame is of a U-shape with one complete open side.

40 The metal that is disturbed by forming the side slot 29 is bent at a right angle with respect to the upper plate 26 and forms an up-standing bracket 30, for a purpose that will presently be explained.

45 The frame snugly fits into the recess 24 that is formed in the lower body-part 10 but the upper plate 26 of the frame is provided with two ears 31 at the upper and lower edges thereof which ears project over the 50 marginal edge of the said recess so that retaining screws may rigidly hold it down in the recess.

Between the upper and lower plates 26-27 of the frame I locate a snap-switch yoke 32, which is shown in perspective in Fig. 9 of the drawings. This yoke has two vertically disposed side bars and two connecting end bars whereby to form a rectangular yoke frame and from one end bar there projects a pin 33.

Each side bar of the switch yoke is provided with a bottom edge lug 34 in which there is formed a notch 35, and each side bar has a pintle perforation 36 directly over the 65 notch therein.

By reference to Figs. 6 and 9 of the drawings, it will be seen that the perforations 36 and the notches 35, are located nearer to one end of the yoke than the other and so that when the yoke is pivotally sustained through the perforations 36 such pivot will be nearer one end than the other. The purpose of this will presently be explained.

The snap switch yoke fits snugly between the plates 26-27 of the switch-frame with the two side bars of the yoke confronting the inner sides of said plates and a pintle pin or screw 37 pivotally connects the yoke with the said plates whereby the yoke may rock between said upper and lower plates. When in place between the plates the pin 33 of the yoke projects through the side gap or slot 29 as shown in Fig. 6 of the drawings.

Beneath the switch yoke and between the plates 26-27 there is a loosely mounted cross-stud 38, which latter has a diametrically-extending pin-passage or perforation 39 extending therethrough and a stem 40 has its lower end extending freely through the pin passage while its upper end carries a cross-head 41 whose outer ends 42, loosely fit into the notches 35 of the yoke while its central portion 43, projects between the two side bars of the yoke.

A coiled spring 44, encircles the stem 40 and is compressed between the cross-stud 38 and the cross-head 41 so that said spring constantly pushes upwardly under the cross-head and presses the ends 42 of said head up into the notches 35 of the side bars of the yoke. As this upward pressure of the stem against the yoke is at a point beneath the pivot perforations 36, if the yoke be rocked on the pin or screw 37 such rocking will cause the upper end of the stem 40 to swing beneath the pin or screw from one side to the other of the latter and as it passes beneath the center of the screw to exert an upward push on the yoke that will cause the latter to snap in the direction in which it is being urged.

The lower end 45 of the yoke is the contact-engaging end thereof and has position in a plane between, but normally spaced from, the yielding contact ends 20 and 22 of the two conductor plates 18 and 21 respectively so that when the yoke is rocked said end 45, will swing up while the pin 33 in the opposite end is depressed and after the yoke has swung far enough to shift the stem 40 and its cross-head 41, to the left of the center of the screw 37 shown in Fig. 6, the coiled spring 44 will cause the yoke to snap forward and drive the end 45 between the contact ends 20 and 22 thereby making a quick snap contact engagement with said contact ends.

The preliminary movement of the yoke is effected manually by a lever 46, that engages the pin 33 of said yoke but the actual snap contact of the yoke is made quickly after the

lever 46 has moved the yoke until the stem 40 is rocked past the center of the pivot screw 37.

In accordance with my invention, I construct this snap switch so that the yoke will normally be held out of engagement with the contact ends 20 and 22 and further that it must be manually held in engagement with said contact ends and in addition to these features the switch shall make a snap engagement with the contacts and a snap disengagement from said contacts.

The snap operation to engage and disengage the yoke with and from the contacts 20-22 is effected, as explained, by the stem 40, spring 44 and the cross-head 41, but the preliminary movement imparted to the yoke to enable the stem, spring and cross-head to produce the snap operation is effected by the manually controlled lever 46, which lever is manually operated against the action of a spring to close the circuit and must be held against the action of that spring as long as such contact is to be maintained because when the lever is released its spring causes the preliminary recoil movement to the yoke which movement is then completed by the yoke-spring 44 and stem 40 to effect a snap opening of the circuit.

The construction and arrangement of the manually controlled lever 46 will therefore now be explained.

The up-standing bracket 30 formed with the material removed from the switch frame in producing the side gap or slot 29, sustains a cross-pin 47 on which the lever 46 is pivotally mounted and the inner end of this lever is bifurcated so as to produce two spaced prongs 48, which latter straddle the pin 33 on the end of the yoke. The outer end of the lever 46 is engaged with an insulating handle 49 which latter extends through a slot 50 in the cover or body-part 11 as shown in Fig. 5 of the drawings.

A coiled spring 51 is wound about the lever pin 47 and has one end engaged with the lever and the other end engaged with the bracket 30 and the tension of this spring is such as to normally hold the lever 46 in a position that will enable one of the prongs 48 to engage the yoke pin 33, and maintain the yoke in a cut-out position but when the lever is swung against the tension of the coiled spring 51 the other prong 48, will engage the pin 33 and impart the preliminary movement to the yoke until the latter is swung over far enough to permit its spring 44, to snap it forward.

The lever 46-49 will then be held by the hand of the operator as long as it is desired to keep the switch closed but when released, either intentionally or by accident and without any thought as to cutting off the current, the lever will spring back and will thus impart a preliminary release to the yoke until

the spring 44 again takes up the recoil movement and effects a snap-off of the switch.

The entire structure is such that when attached to the tool such as a sad iron 52, the actuating lever 49, will be in close proximity to the handle 53 of the iron so that as the handle is grasped to manipulate the iron the lever 49 may be held up and the switch thus held closed.

If the operator of the tool releases the latter such release will cause the lever 49 to move so as to automatically cut off the current and the cutting off will be effected by a snap operation so as to prevent arcing of the current.

Having described my invention, I claim:—

1. The combination with an electric hand tool having a handle and provided with means for engaging a terminal body on the end of a flexible wire connection, of a separate body of substantially flat, oblong form having connectors for detachably engaging said means on the tool, a switch structure enclosed entirely within the said body, manual means supported entirely by and within the body and extending from the latter past the side of the handle of the electric hand tool and below the handle grip so it may be engaged by the fingers of the hand holding the tool, said manual means being entirely free of and altogether disconnected from said tool-handle and extending through the wall of said body so as to actuate the switch within the body for closing the circuit and holding the same closed as long as the same is held by the fingers of the hand holding the tool, said manual means being confined at all times substantially within the lateral limits of the tool handle grip, and means for automatically returning the manual means when the same is released and causing the switch to snap open.

2. In a socket structure the combination with a self-contained body having readily attachable and detachable connectors for engaging a hand tool and provided with spaced contact plates, of a pivoted switch lever in the body for co-operation with said contact plates, spring means arranged with respect to the pivot point of said switch lever so as to snap the switch lever to either closed or open position after the lever has been moved past dead-center, a hand lever engaging the switch lever to actuate the same, said hand lever being provided with a spring whereby it is normally actuated so as to effect an opening of the switch but arranged to be held manually so as to maintain the switch closed, whereby upon release of the hand lever the same will automatically move to normal position and thereby open the switch.

3. In a socket structure the combination with a self-contained body having readily attachable and detachable connectors for engaging a hand tool and provided with spaced

contact plates, of a snap-switch yoke pivoted as a single member within the body, spring means having direct engagement with the pivotal region of the yoke for snapping the same to either a closed or open position after the yoke has been moved past dead-center, and a spring actuated hand lever having its spring housed within said body for yieldingly holding the yoke in a cut off position, whereby the hand lever may be moved manually and held as long as it is desired to keep the yoke in a closed position.

In testimony whereof I affix my signature.

GEORGE EATON.
